(57) CLAIM

The ornamental design for an animal cage, as shown and described.

DESCRIPTION

FIG. 1 is a front perspective view of an animal cage showing my new design.

FIG. 2 is a top plan view thereof.

FIG. 3 is a right side elevational view thereof, with the left side elevational view being a mirror image of the right side shown.

FIG. 4 is a rear elevational view thereof.

FIG. 5 is a front elevational view thereof.

FIG. 6 is a bottom plan view thereof.

FIG. 7 is a front perspective view thereof with the lid removed.

FIG. 8 is a top plan view of FIG. 7.

FIG. 9 is a right side elevational view of FIG. 7.

FIG. 10 is a rear elevational view of FIG. 7.

FIG. 11 is a front elevational view of FIG. 7; and,

FIG. 12 is a bottom plan view of FIG. 7.

The broken lines are for illustration only and form no part of the claimed design.
